UNITED STATES PATENT OFFICE.

JOSEPH A. POIRIER, OF WOONSOCKET, RHODE ISLAND.

TAPE-FEEDING DEVICE.

No. 920,644.

Specification of Letters Patent.

Patented May 4, 1909.

Application filed September 22, 1908. Serial No. 454,160.

To all whom it may concern:

Be it known that I, JOSEPH A. POIRIER, a subject of the King of England, residing at Woonsocket, in the county of Providence 5 and State of Rhode Island, have invented new and useful Improvements in Tape-Feeding Devices, of which the following is a specification.

My invention pertains to paper box machinery and more particularly to means for feeding binding tape to paper boxes incidental to the manufacture of the same; and it contemplates the provision of a simple and inexpensive device which is adapted to 10 feed binding tape step by step without liability of the tape sticking and causing waste thereof, and is also adapted to be quickly and easily cleared of collected paste, and is otherwise practically advantageous. 15 With the foregoing in view the invention will be fully understood from the following description and claims when the same are read in connection with the drawings, accompanying and forming part of this specification, in which:

Figure 1 is a side elevation of so much of a box making machine or apparatus as is necessary to illustrate the best practical embodiment of my invention of which I am 20 cognizant. Fig. 2 is a transverse section, taken in the plane indicated by the line 2—2 of Fig. 1, looking in the direction indicated by arrow, and with the binding tape omitted.

Similar letters designate corresponding 25 parts in both views of the drawings, referring to which:

A is a frame which may form part of or be suitably attached in a fixed manner to the frame of a machine for making paper boxes. 30 B is a sub-frame, pivoted at *a* to the frame A so as to be capable of being raised and lowered, and C is a tractile spring connected to the frame A and detachably connected to a lateral projection *b* on the sub-frame B and having for its office to yieldingly hold the sub-frame down in the position illustrated and yet permit of said sub-frame being swung upwardly when necessity demands, as will be hereinafter pointed 35 out.

On the frame A is a lateral journal *c*, and on said journal is removably arranged a wheel D having a perimeter of V-shape in cross-section, as best shown in Fig. 2, and 40 above the said wheel D is a comparatively large wheel E having a circumferential

groove *d* which is of V-shape in cross-section to receive the peripheral portion of the wheel D and is milled or provided on its walls with minute crosswise grooves *e* in 45 order to enable it to take better hold of and positively feed the binding tape which is indicated by F in Fig. 1.

The comparatively large and circumferentially grooved wheel E is loosely mounted 50 on a journal *f* extending laterally from the sub-frame B, and is provided at one side with an annular flange *g*. This flange *g* is for the engagement of the kerfed heads or portions *h* of dogs G, the inner ends of which 55 are disposed in notches *i* provided in a vertically swinging body H loosely mounted on the journal *f* and retained against lateral displacement by a washer I and a nut J or other means suitable to the purpose. The 60 said swinging body or piece H is provided with three arms *k* *l* and *m*; the arms *k* and *l* being connected by coiled springs K with apertured lugs *n* on the dogs G, and the arm *m* being connected to a rod L, which is 65 designed to derive a reciprocatory motion from a suitable working part (not shown) of a box-making machine. As clearly shown by dotted lines in Fig. 1, the notches *i* are 70 respectively provided with a wall *i*², disposed radially to the center of movement of the swinging body H.

At the left of the wheels D and E and the appurtenances thereof I prefer to arrange a spool P for the binding tape, and a tank R 75 for water, the tank being arranged intermediate the spool and the wheels D and E, and being equipped with idler rollers S and with a drum T, the office of which latter is to take up water from the tank and apply the same 80 to the gummed side of the tape. When, however, a tape that is not gummed is to be used, the drum T may be utilized to apply 85 paste or gum to the tape, or in other words transfer paste or gum from the tank R to the 90 tape incidental to the passage of the latter to the wheels D and E.

In the practical operation of my novel device it will be manifest that when the rod L is reciprocated, the swinging body H will be 95 oscillated, and that on movement of the said parts in the directions indicated by arrows in Fig. 1, the walls *i*² of the notches *i* will serve to engage the inner ends of the dogs G and bind the kerfed portions of the dogs against 100 the annular flange *g* of the wheel E, with the result that the said wheel E will be turned 105

through a part of a revolution in the said direction. On the succeeding movements of the rod L and swinging body H in the directions opposite to those indicated by the arrows, the kerfed portions of the dogs G will slip over the flange *g* of wheel E without transmitting motion to said wheel. From this it will be understood that the wheel E is turned step by step in one direction only, which is materially advantageous inasmuch as it assures proper feed of the binding tape and precludes sticking of the tape and the consequent loss of more or less of the same. The binding tape which is used to secure the corners of paper boxes passes in a flat state from the spool P and over the drum T, but during the feed of the said tape between the wheels D and E it is reduced to V-shape in cross-section so as to conform to the shape of the corners of the box that is being made.

Because of the gummed side of the tape being presented to the wheel D, gum collects on the said wheel. This makes it necessary to clean the said wheel D at intervals, and when the same is to be done the spring C is disconnected from the lateral projection *b* of the sub-frame B and said frame B is swung upwardly so as to carry the wheel E out of engagement with the wheel D, whereupon the latter may be readily moved off of the journal *c*.

It will be gathered from the foregoing that by virtue of the wheel E being considerably larger in diameter than the wheel D to which the gummed side of the tape is presented, the said wheel D is turned at a high rate of speed, and consequently the tape does not have time to adhere to the wheel D which obviously lessens the liability of the tape sticking in the device.

The construction herein illustrated and described constitutes the best practical embodiment of my invention of which I am cognizant, but it is obvious that in the future practice of the invention such changes or modifications may be made as fairly fall

within the scope of my invention as defined in the claims appended.

Having described my invention, what I claim and desire to secure by Letters-Patent, is:

1. In a tape feeding device, the combination of a frame, a wheel mounted on said frame, a sub-frame connected with the main frame and movable toward and from the said wheel, a wheel carried by the sub-frame and having an annular flange at one side, a spring connecting the first-named frame and the sub-frame and adapted to yieldingly hold the second-named wheel against the first-named wheel, a swinging body carried by the sub-frame and mounted alongside the second-named wheel and having three arms and also having notches, dogs having their inner ends disposed in said notches and also having kerfed portions for engaging the said flange, springs connecting the dogs and two of the arms of the swinging body, and a reciprocating rod connected to the third arm of the swinging body.

2. In a tape feeding device, the combination of a frame having a lateral journal thereon, a wheel removably arranged on said journal and having a perimeter of V-shape in cross-section, a sub-frame connected with the main frame and movable toward and from the said wheel, a wheel carried by the sub-frame and having a circumferential groove normally receiving the perimeter of the first named wheel, and a spring detachably connecting the first named or main frame and the sub-frame and adapted to yieldingly hold the second named wheel against the first named wheel.

In testimony whereof I have hereunto set my hand in presence of two subscribing witnesses.

JOSEPH A. POIRIER
